UNITED STATES PATENT OFFICE.

OLAV ESKIL JÖRGENSEN, OF NEW YORK, N. Y.

POWER-TRANSMITTING DEVICE.

Application filed June 17, 1920. Serial No. 389,575.

To all whom it may concern:

Be it known that I, OLAV ESKIL JÖRGENSEN, a subject of the King of Denmark, residing at New York city, county of New York, and State of New York, have invented certain new and useful Improvements in Power-Transmitting Devices, fully described and represented in the following specification and the accompanying drawings, forming a part of the same.

This invention relates to power transmitting devices, and particularly to reversing gear for engines.

In engines such as Diesel engines, for example, of the type in which the engine valves are operated by means of forward and reverse cams, the shift from one set to the other may be accomplished either by shifting the cam shaft or the cam rollers.

In either case it is desirable to move the cam rollers away from the cams prior to the shifting operation.

It is the principal object of the present invention to provide a power transmitting device, particularly adaptable as a reversing gear for engines, having a sufficient force that is easily manipulated, and such that the power transmitting movements are not precipitous but are properly held in check.

With this general object in view, the invention consists in the combinations, details of construction and arrangement of parts which will first be described in connection with the accompanying drawing and then more particularly pointed out.

In the drawing—

Figure 1 is a diagrammatic view with parts in vertical cross section of a power transmitting device constructed in accordance with the invention, and

Figure 2 is a sectional view similar to part of Fig. 1 taken on a different section line.

In carrying out the invention according to the exemplification here illustrated, power is derived from a source of compressed air or the like. This force is delivered to one or the other of two communicating cylinders containing oil or a like liquid, while the other cylinder is open to exhaust. The force of the compressed air moves a piston in one of the cylinders and through suitable mechanism the piston's movement shifts the cam rollers away from and back to the cam. This movement is held in check by throt-

tling the flow of oil from one cylinder to the other.

Referring to the drawing, in a cylinder 3 slides a piston 4 having a piston rod 5 adapted to be connected with the power-receiving mechanism as hereinafter described. The cylinder 3 below the piston, contains a power-transmitting liquid 6, such, for example, as oil. Communicating with cylinder 3 is a second cylinder 7 also containing the oil or like liquid.

Connections are provided for supplying a fluid under pressure to either cylinder above the liquid and for opening the other cylinder to exhaust. Although capable of various constructions, in that illustrated as an example, a pipe 8 opening into the top of cylinder 3 leads through a 3-way valve 9 to a pipe 10 adapted to connect with a source of compressed air or the like. A pipe 11 leading from the top of cylinder 7 to valve 9 connects that cylinder with supply pipe 10.

Also opening into the top of cylinder 3 is an exhaust pipe 12 leading to atmosphere or the like. Pipe 12 is opened or closed by a valve 13. A similar exhaust pipe 14, having a control valve 15, leads from the top of cylinder 7.

Means is provided for throttling the flow of liquid from one cylinder to the other, and for normally preventing flow. This may be accomplished, for example, by two heavily loaded check valves. Although capable of various constructions, in that illustrated, in a passage 16 connecting the two cylinders, is a check valve 17 permitting flow from cylinder 3 to cylinder 7 but preventing opposite flow. The opening of this valve is opposed by a loading spring 18 the force of which is adjustable by means of a nut 19.

In a second passage 20 is a check valve 21 arranged to permit flow from cylinder 7 to cylinder 3 and to prevent opposite flow. The opening of this valve is similarly opposed by a spring 22 having an adjusting nut 23.

The invention includes in its entirety, in connection with an engine cam shaft, a cam roller having a shiftable support and an operating connection between such support and the piston rod. This cam-roller support and its operating connection may vary widely in construction. In the exemplification here illustrated diagrammati-

2
cally, the engine cam shaft 25 has one or more sets of cams 26, one cam of each set being for "forward," the other for "reverse." Cooperating with each set of cams 5 is a cam roller 27 journaled in a support 28 on the end of a valve rod 29. Pivoted to the valve rod 29 is a shifting link 30, the other end of which is connected to an eccentric 31 secured to a shaft 35. This shaft is 10 rotated by a gear 36 mounted thereon, which meshes with a swinging segmental gear 37 pivotally connected to the piston rod 5.

Under normal conditions and the engine 15 operating "forward" all the valves are closed and the parts remain in a state of rest or balance as shown in Figure 1. When it is desired to reverse the engine, cylinder 3 is opened to exhaust by valve 13 and valve 20 9 is operated to connect cylinder 7 with the air supply pipe 10. The force of the compressed air causes the oil to flow from cylinder 7 to cylinder 3, valve 21 being forced open against its spring. This movement of 25 the oil raises piston 4 and piston rod 5 and swings segmental gear 37 to rotate gear 36, thus rotating shaft 35 one revolution. By the resulting operation of the several eccentrics 31 the links 30 are first pulled to 30 the right, as viewed in Fig. 1, and then returned to initial position. The first part of this movement swings the lower ends of the valve rods away from normal position, the valve rods being jointed, as at 33. Thus 35 the cam rollers are shifted away from their cams. While so shifted the cams are shifted for "reverse" (by means not shown). During the latter part of the rotation of shaft 35, the opposite movement of links 30 returns the lower ends of the valve rods to 40 normal position for the operation of the valve rods by the now operative "reverse" cams. The air-controlling valves are then closed again to place the parts in a state of 45 balance, with the piston 4 at the upper end of its movement in cylinder 3, flow of oil between the cylinders being prevented. It will be seen from Figure 1 that, in the embodiment illustrated, in the normal position 50 of the parts, there is a direct thrust along the links 30, thus locking the parts in position. Preferably, the shifting movement of the piston is such that the shaft 35 is given a full revolution, as shown, so that direct 55 thrust is secured in both the normal and extreme inward position of the links, but this may be varied.

For the return movement from "reverse" 60 to "forward," valve 15 is opened to connect cylinder 7 with exhaust and valve 9 is operated to connect cylinder 3 with the air supply pipe. The force of the compressed air against piston 5, forces the latter downwardly against the oil which flows through 65 passage 16 into cylinder 7, valve 17 being

forced open. This movement of the piston, as will be apparent, rocks shaft 35 in the opposite direction and thus causes the links 30 to withdraw the valve rods 29 for shifting the cams, and returns the valve rods to 70 normal position for "forward" operation. The valves 9, 15 and 17 are then closed and all the parts are again in the position shown in Figure 1, being again held in a state of 75 balance.

With the apparatus described a powerful and easily manipulated force is provided for shifting the cam rollers. At the same time the flow of the oil from one cylinder to the other is so throttled, by the loaded check valves 17 and 21 in the passages 16 and 20, that the power-transmitting movement is properly held in check and timed as desired.

It is to be understood that the apparatus 85 shown is illustrative only and changes may be made within a wide range without departing from the invention.

What I claim is:

1. In a reversing device for engines, and 90 the like, a cam roller, a shiftable support for said cam roller, a piston, a cylinder in which said piston reciprocates and which contains a liquid below the piston, a second cylinder 95 communicating with the first cylinder and also containing a liquid, connections for supplying a fluid under pressure to either cylinder and opening the other cylinder to exhaust, an operating connection between the piston rod and said shiftable support, and means for normally preventing a flow of the liquid from one cylinder to the other.

2. In a reversing device for engines, and 105 the like, a cam roller, a shiftable support for said cam roller, a piston, a cylinder in which 110 said piston reciprocates and which contains a liquid below the piston, a second cylinder communicating with the first cylinder and also containing a liquid, connections for supplying a fluid under pressure to either cylinder and opening the other cylinder to exhaust, an operating connection between the 115 piston rod and said shiftable support, and means for throttling the flow of the liquid from one cylinder to the other.

3. In a reversing device for engines, and 120 the like, a cam roller, a shiftable support for said cam roller, a piston, a cylinder in which 125 said piston reciprocates and which contains a liquid below the piston, a second cylinder communicating with the first cylinder and also containing a liquid, connections for supplying a fluid under pressure to either cylinder and opening the other cylinder to exhaust, an operating connection between the piston rod and said shiftable support, and oppositely disposed loaded check valves 130 between said cylinders.

4. In a reversing device for engines, and 130 the like, a cam roller, a shiftable support

- therefor, an eccentric for shifting said support, a link between said support and said eccentric, having a direct thrust when in a position of rest, thereby to lock the parts, a
5 reverse-acting, fluid-pressure device for rotating said eccentric, and means whereby said device may be held in a state of balance.
5. In a reversing device for engines, and the like, a cam roller, a shiftable support
10 therefore, a piston, a cylinder in which said piston reciprocates and which contains a liquid below the piston, a second cylinder communicating with the first cylinder and also containing a liquid, a pipe connected
15 with each cylinder for supplying a fluid

under pressure thereto, a pipe connected with each cylinder for opening the same to exhaust, valves for controlling flow through said pipes, whereby either cylinder may be opened to the pressure fluid and the other cylinder opened to exhaust, a connection between the piston and the shiftable support for shifting the support away from and back to normal position upon one stroke of said piston, and means for preventing liquid flow
20 between the cylinders when all of said valves are closed.

In testimony whereof, I have hereunto set my hand.

OLAV ESKIL JÖRGENSEN.
